Patented Feb. 23, 1915.

UNITED STATES PATENT OFFICE.

CHARLES A. CARSCADIN AND GEORGE A. WOODMAN, OF CHICAGO, ILLINOIS.

UNCOUPLING DEVICE.

1,129,070.

Specification of Letters Patent. Patented Feb. 23, 1915.

Application filed September 8, 1913. Serial No. 788,526.

To all whom it may concern:

Be it known that we, CHARLES A. CARSCADIN and GEORGE A. WOODMAN, citizens of the United States, both residing at Chicago, in the county of Cook and State of Illinois, have jointly invented certain new and useful Improvements in Uncoupling Devices, of which the following is a specification.

Our invention relates in general to uncoupling devices such as are in use upon railway cars and the like and aims to provide a new and improved means for lifting the locking pin of a coupler of any of the ordinary types.

One of the principal objects of our invention is to provide a car uncoupling device which may be operated from the side of the car and which will be so constructed that the operating rod may be connected directly to the locking pin of the coupler, obviating thereby the use of chains, links and clevises, which are at present employed in many forms of devices of this character to connect the operating rod to the locking pin. The use of uncoupling devices employing these members to connect the operating rod to the locking pin of the coupler has subjected the railway companies to considerable annoyance and expense by reason of the theft of these parts, which has thereby rendered the uncoupling device inoperative and required the brakeman to enter between the cars to couple and uncouple them at great risk to himself and in violation of the regulations of the railway commission. Our invention aims to overcome this and other disadvantages by providing a new and improved uncoupling device wherein all of the parts which can be easily and surreptitiously removed will be eliminated, and which at the same time can be readily applied to the car and easily operated.

A still further object of the invention is to provide an uncoupling device possessing these and other advantages, which will be of simple and cheap construction and which will be durable and efficient in use.

Further aims and advantages of our invention will be apparent from the following description as it is better understood when taken in connection with the accompanying drawing illustrating preferred embodiments thereof.

On the drawing, Figure 1 is a top plan view of a portion of a car and coupler provided with an uncoupling device embodying

our invention; Fig. 2 is an enlarged transverse section through the inner bracket and slide provided to connect the inner end of the operating rod to the car; Fig. 3 is a horizontal section taken substantially on the line 3—3 of Fig. 2; Fig. 4 is an enlarged side elevation of the slide; Fig. 5 is a transverse section similar to Fig. 2 of a somewhat different embodiment of our invention, and Fig. 6 is a similar view of still another embodiment.

Referring to the drawing, the invention comprises an operating rod 10, an outer bracket 11, an inner bracket 12 and a slide 13 carried by the bracket 12, the rod 10 passing through the bracket 11 and slide 13 as will be later described. In the present instance the operating rod is connected directly to the locking pin of the coupler by an arm 14 extending outwardly from the car at right angles to the body portion of the rod and inserted through the eye 15 of the locking pin 16, the end of the arm 14 being bent at 17 to prevent its disconnection from the locking pin when the parts are in operative position upon the car. The bracket 11, which embraces the outer end of the operating rod, is secured to the car at 18 adjacent one side so that the operating arm 19 at the end of the body portion of the rod adjacent the side of the car may be operated without requiring the brakeman to enter between the cars to couple and uncouple them. The bracket 11 is of the ordinary construction except that the aperture 21 is formed to permit the operating rod to move pivotally about the bracket 11 as a center through a limited arc as the coupler head is pulled from or pushed toward the car in service.

The bracket 12 consists in the present instance of a base-plate 22 of suitable formation to be secured to the car by bolts or other fastening means 23 extending through apertures 24 in the fastening plate. This fastening plate is provided with a horizontally disposed rail or bracket arm 25. In the embodiment of the invention shown in Figs. 1 to 4 this arm is of T-shaped form consisting of a supporting web 26 carrying a flattened head 27. The head 27 extends throughout the length of the arm and is embraced by the slide 13 carrying the operating rod. The slide 13 is formed at its bottom with a T-shaped slot 28 adapted to fit over the bracket arm 25 and permit the slide to move longitudinally of the car upon the bracket arm.

The slide 13 is preferably provided with an upwardly extending web 29 having an elongated longitudinally disposed slot 30 through which the operating rod 10 is disposed, as indicated in dotted lines in Fig. 4. 5 Adjacent the forward end of the bracket arm are provided outwardly extending webs 31 and the width of the opening of the slot 28 is preferably just sufficient to permit the body portion of the slide to move easily past these webs as it moves backward and forward when the cars are in service. At the rear end of the slide a pair of stops 32 extend inwardly of the opening of the slot 28 to adjacent the web 25 of the bracket arm, thus disposing them in position to engage the webs 31 of the bracket arm to prevent excessive outward movement of the slide with respect to the bracket 12. 10 In Fig. 5 a somewhat modified form of our invention is disclosed wherein the slide which embraces the operating rod consists of a hollow casting 33 provided with a pair of parallel elongated longitudinally extending slots 34, through which the operating rod 10 is disposed. The lower edges 35 of the casting are inturned to provide a slot embracing the bracket arm 36, which in this embodiment of the invention is identical in shape and construction with that described in connection with Figs. 1 to 4. In order that the casting may be held in proper position upon the bracket arm the sides of the casting are deflected inwardly at 37 to 25 engage the upper surface of the bracket arm. 30 In Fig. 6 a third embodiment is set forth wherein the bracket arm 38 is provided with a rounded bearing surface 39 and the slide 41 is provided with a slot of suitable shape 40 to engage and slide upon the surface 39. In this embodiment the lower edges 42 of the slide engage the central supporting web 43 of the bracket arm and the webs 44 on this arm are provided to act as stops and terminate a substantial distance beneath the portion of the bracket arm embraced by the slide and suitable downwardly extending stops 45 are provided to engage the upper ends of these webs to prevent excessive outward movement of the slide with respect to 45 the bracket arm.

An uncoupling device made in pursuance of our invention may be positioned upon the car by inserting the end of the operating rod through the slot in the slide and through the aperture in the bracket 11. The bracket 12 is then connected with the slide by moving the front of the slide over the rear of the bracket arm into normal position when, 55 after engaging the lifting arm 14 in the eye of the locking pin of the coupler, the two brackets 11 and 12 may be secured in place. The bracket 12 is preferably mounted close to the car body so that the slide can not be 60 moved rearwardly to disengage it from the 65

bracket arm of this bracket. The preferable normal relative relation between the operating rod and the slide 13 and bracket 12 is that shown in Figs. 1 and 4. When the slide is in its rearmost position, the operating rod is preferably disposed adjacent the front end of the slot of the slide. This permits the operating rod to move inwardly to substantially against the car body and to move outwardly throughout the full length of the sliding movement between the slide and bracket member. It will be apparent that the proper dimensions of the parts may be readily determined to give the operating rod the freedom of movement necessary to move with the coupler as the coupler head is pulled away from or pushed toward the car. 70 75 80

The parts are few in number, simple and may be cheaply constructed, and when connected as described, can none of them be removed without detaching one of the brackets fastened to the car. 85

It will be apparent that various changes may be made in the form, construction and arrangement of the parts without departing from the spirit or scope of the invention or sacrificing any of its material advantages, the forms hereinbefore disclosed being merely preferred embodiments thereof. 90 95

We claim:

1. An uncoupling device for railway cars comprising an operating rod adapted to be secured to a car and having a lifting arm adapted to be engaged to the locking pin of the coupler, and means for securing said operating rod to the car, said means comprising a bracket having a single rail adapted to extend longitudinally of said car, and a slide carrying said operating rod and interlockingly engaging said bracket rail to slide longitudinally thereof. 100 105

2. An uncoupling device for railway cars comprising an operating rod adapted to be secured to a car and having a lifting arm adapted to be engaged to the locking pin of the coupler, and means for securing said operating rod to the car, said means comprising a bracket having a single rail adapted to extend longitudinally of said car, and a slide carrying said operating rod and interlockingly engaging said rail to slide longitudinally thereof, said slide having an elongated slot embracing said operating rod to permit said operating rod to slide longitudinally of said slide and bracket rail. 110 115 120

3. An uncoupling device for railway cars comprising an operating rod adapted to be secured to a car and having an arm adapted to be connected to the locking pin of the coupler, and means for securing said operating rod to the car, said means comprising a bracket having a single rail adapted to extend longitudinally of the car, a slide interlockingly engaging said rail and adapt- 125 130

ed to slide longitudinally thereof and stops on said bracket arm and on said slide for limiting relative movement therebetween.

4. An uncoupling device for railway cars comprising an operating rod adapted to be secured to a car and having an arm adapted to be connected to the locking pin of the coupler, and means for securing said operating rod to the car, said means comprising a bracket adapted to be secured to the car and provided with a single rail adapted to be disposed longitudinally of said car, and a slide carrying the operating rod embracing said rail and adapted to slide longitudinally thereof.

5. An uncoupling device for railway cars comprising an operating rod adapted to be secured to a car and having an arm adapted to be connected to the locking pin of the coupler, and means for securing said operating rod to the car, said means comprising a bracket adapted to be secured to the car and having a bracket arm adapted to extend longitudinally of the car, and a slide 20 slidably connected to said arm and extending upwardly above said arm, said upwardly extending portion being provided with a slot through which said operating rod is disposed and said slot and said sliding connection between the arm and slide permitting the operating rod to move outwardly beyond the outer end of said arm when the parts are in operative position.

6. An uncoupling device for railway cars comprising an operating rod adapted to be secured to a car and having an arm adapted to be connected to the locking pin of the coupler, and means for securing said operating rod to the car, said means comprising a bracket adapted to be secured to the

car and having a bracket arm adapted to extend longitudinally of the car, and a slide embracing said arm and provided with an upwardly extending web having an elongated longitudinally extending slot through 45 which said operating rod is disposed.

7. An uncoupling device for railway cars comprising an operating rod adapted to be secured to a car and having an arm adapted to be connected to the locking pin of the coupler, and means for securing said operating rod to the car, said means comprising a bracket having a bracket arm adapted to be disposed longitudinally of the car, the upper portion of said arm being enlarged, 50 and a slide carrying said operating rod embracing the enlarged portion of said arm and slidably thereon.

8. An uncoupling device for railway cars comprising an operating rod adapted to be secured to a car and having an arm adapted to be connected to the locking pin of the coupler, and means for securing said operating rod to the car, said means comprising a bracket having a bracket arm adapted 60 to be disposed longitudinally of the car, the upper portion of said arm being enlarged, and a slide carrying said operating rod embracing the enlarged portion of said arm and slidably thereon, said arm being provided with outwardly extending stops beneath said enlarged portion and said slide being provided with inwardly extending slots at the rear end of its base adapted for engagement with the stops on said arm.
